DESIGN FOR A HELICOPTER

Robert A. Wolf, Kenmore, N. Y., assignor to Bell
Aircraft Corporation, Wheatfield, N. Y.

Application June 23, 1945, Serial No. 120,299

Term of patent 14 years

(Cl. D71—1)

To all whom it may concern:

Be it known that I, Robert A. Wolf, a citizen of the United States, residing at Kenmore, in the county of Erie and State of New York, have invented a new, original, and ornamental Design for a Helicopter, of which the following is a specification, reference being had to the accompanying drawings, forming part thereof.

Figure 1 is a top plan view of a helicopter showing my novel design.

Figure 2 is a front end elevational view of the helicopter shown in Figure 1.

Figure 3 is a side elevational view thereof.

Fig. 4 is a bottom plan view thereof; and

Figs. 5, 6, 7 are diametric outlines of sectional views taken along lines V—V, VI—VI, and VII—VII, respectively, of Fig. 3.

I claim:

The ornamental design for a helicopter, as shown.

ROBERT A. WOLF.
